(57) **CLAIM**

The ornamental design for a connector housing, as shown and described.

DESCRIPTION

FIG. 1 is a perspective view of a connector housing showing my new design;

FIG. 2 is a top plan view thereof;

FIG. 3 is a front elevation view thereof;

FIG. 4 is a bottom plan view thereof;

FIG. 5 is a first-side elevation view thereof;

FIG. 6 is a rear elevation view thereof;

FIG. 7 is a second-side elevation view thereof;

FIG. 8 is a second-side elevation view thereof, in use condition; and,

FIG. 9 is a second-side elevation view thereof, not in use condition.

The broken line portion of the figure drawings is included to show unclaimed subject matter only and forms no part of the claimed design.
